UNITED STATES PATENT OFFICE.

SAMUEL B. MOSCOVITZ, OF NEW YORK, N. Y., ASSIGNEE, BY MESNE ASSIGNMENTS, TO
NATIONAL AUTOMATIC ROLL ADVERTISING COMPANY, A CORPORATION OF NEW
YORK.

ELECTRICAL INDICATOR.

1,076,222.

Specification of Letters Patent.

Patented Oct. 21, 1913.

Application filed August 28, 1907. Serial No. 390,480.

To all whom it may concern:

Be it known that I, SAMUEL B. MOSCOVITZ, a citizen of the United States, and a resident of New York, county of New York, and State of New York, have invented certain new and useful Improvements in Electrical Indicators, of which the following is a specification.

The present invention pertains to that 10 class of apparatus which is employed for indicating the names of railway stations, street crossings and for the display of bulletins and advertising matter.

The object of my invention is to provide 15 an efficient automatic mechanism principally for use in street or railway cars to visually announce the stations or street crossings to passengers. But the apparatus may also be utilized for other purposes in public places, 20 as to, for instance, indicate the arrival and departure of trains, etc.

When used in street or railway cars, apart 25 from indicating the names of stations or street crossings, it may show different business places located in the neighborhood of the approaching street or station.

My invention thus consists in the construction and combination of parts which render the mechanism simpler and cheaper 30 and at the same time more efficient than those hitherto known.

In order that my invention may be fully understood, the same is illustrated in the 35 accompanying drawings in which similar reference numerals denote corresponding parts and in which—

Figure 1 is a front elevation of the apparatus; Fig. 2 a vertical cross section through line 2, 2 of Fig. 1 and looking to 40 the left; Fig. 3 a vertical cross section through line 3, 3 of Fig. 1 and looking to the left; Fig. 4 a left side view; Fig. 5 a vertical cross section through line 5, 5 of Fig. 1 and looking to the right; Fig. 6 a vertical cross section through line 6, 6 of Fig. 1 and looking to the left; Fig. 7 a right side view; Fig. 8 a horizontal cross section on line 8—8 of Fig. 7; Fig. 9 a similar section on line y—y of Fig. 1; Fig. 10 50 a diagram showing the electric circuits.

With reference to the drawings 1 denotes the main frame in which the rollers for feeding, winding and guiding the strip or band that bears the matter to be indicated are

supported. To both sides of this frame auxiliary frames 2, 3 are secured for the support of a suitable motor and of the main mechanism for operating the rollers.

The strip or band 4 which may be made of any suitable material is adapted to bear 60 the matter to be indicated on both sides, so that the indications may be seen from both sides of the apparatus.

The upper and lower ends of the band are 65 permanently secured to winding rollers 5, 6 arranged vertically one above the other and rigidly secured on shafts 7, 8 respectively, said shafts extending longitudinally of the frame 1 and being rotatively supported 70 therein. Between these two rollers 5 and 6 the feed-roller 9 is provided, the axis of which extends in the same vertical plane with the two mentioned winding rollers. This feed-roller may be of any suitable construction. Thus, for instance, it may be 75 provided at its ends with a plurality of radial pins 10 that are adapted to engage metallic eyelets 11 provided at the lateral edges of the strip or band 4 to feed the latter as the roller 9 revolves. Above and 80 below the feed-roller 9, guide-rollers 11' and 12 are respectively provided, which are adapted to hold the strip taut against one side of the feed-roller 9. At the lower part 85 of the frame, adjacent to and parallel with the winding roller 6, another guide roller 13 is provided which is adapted to guide in vertical direction and parallel with the front and rear walls and panes 14 of the casing 16, that portion of the strip which extends 90 downward from the feed-roller 9 to the winding roller 6.

The shafts 7, 8 carry at one end sleeves 7', 8' which are frictionally connected therewith to form friction couplings that are 95 geared with the shaft 17 of the feed-roller in a manner, that by the rotation of the feed-roller in one direction, the friction coupling of the winding roller on which the strip is being wound up will be directly driven 100 therefrom, while the other being uncoupled will be allowed to turn under the strain of the feeding strip, and vice versa. For this purpose the shaft 17 of the feed-roller carries at its ends gears 19, 20 that are loosely 105 mounted thereon and are provided with spring actuated pawls 21 adapted to cooperate with ratchet wheels 22 rigidly se-

cured on the shaft 17. The teeth of the two oppositely located ratchet wheels 22 run in reverse directions so that, according to the direction of rotation of the shaft 17, one of 5 the gears at the ends of the shaft will be coupled and caused to revolve therewith, while the other will remain at rest. The bevel gear 19 meshes with a smaller gear 23, that by a spindle 24 and gear 25 is 10 adapted to transmit movement to the gear 26 of the sleeve 8', which by friction will transmit movement to the shaft 8 and roller 6. At the other end of the shaft the gear 20 transmits movement by a gear 27 to the gear 15 28 of the sleeve 7', which by friction will drive shaft 7 and roller 5. In order that the strip be maintained taut notwithstanding the varying diameter of the rollers, upon 20 and from which the strip is wound and unwound, the gearing is so chosen that one revolution of the feed-roller will transmit a certain number of revolutions to the coupled sleeve of the winding roller, which number is decreased by the slipping of the appropriate 25 friction sleeve 7' or 8' as the amount of strip 4 wound up upon the roll increases. It is for this purpose that the friction sleeves 7' and 8' are provided.

At one end of the shafts 7, 8 washers 5', 6' 30 may be arranged so as to bear with slight friction against the walls of the frame 1, whereby the rotation of said shafts may be somewhat retarded. This frictional retardation is sufficient to retard the too rapid unwinding of the strip 4 in response to the pull 35 of the feed-roll 9.

The shaft 17 of the feed-roller is extended into the auxiliary frame 3 and coupled by suitable means with the main shaft 29 of the 40 automatic mechanism that serves to operate the feed and winding rollers. This mechanism consists of two cam disks 30, 31 of equal size and shape, rigidly mounted on shaft 29 so that their cam portions are 45 reversed to one another.

The shaft 29 of the cam disks is connected by a set of gears 32, 33, 34, 35, 36 and 37, suitably maintained in a frame 3, with a shaft 39 borne in the frame parallel to shaft 29. This shaft 39 is connected by a suitable coupling 39' with the shaft 40 which in turn may be connected by a suitable friction coupling 40' with the reversible electric motor 41 supported in frame 2.

At the upper part of frame 3 an electromagnet 42 is arranged which may be fed from an electric battery 43 or any other electric source, and in the circuit of which an automatically operated switch 44 (see 55 diagram Fig. 10) is included. When the apparatus is applied to street or railway cars this switch may be operated from a projection or any suitable means suspended from the underframe of the car.

The armature of the electromagnet is

formed as a swinging plate 45, or the like, which is pivoted in the frame 3 at some distance from the electromagnet, and which at the end below the latter is formed with a downwardly extending frame 46 that at the 70 lower end carries set screws 47, 47.

Mounted on a cross spindle 48, borne in the frame, and capable of swinging up and down independently of each other, are two pawls 49, 50, which extend toward the cam disks 30, 31 and are each adapted to normally rest on the corresponding disk at the lowest point of the periphery of the latter, one in front, the other behind the shoulder 51 formed on the cam disks at this point. Thereby the shaft 29 will be locked against rotation in either direction, and no movement can be transmitted to the feed-roller 80 9 from the motor 41, which may be still in motion. The pawls 49, 50 are projected through the frame 46 and are each adapted to rest upon the set screws 47, 47, the frame allowing them sufficient play for swinging up and down.

When the armature 45 is attracted by the 90 energized electromagnet, the frame 46 will simultaneously lift both pawls, bringing them, when the set screws 47 are properly adjusted to the highest point of the shoulder 51, thus releasing the cam disks, which, when the motor is in operation, will allow of the shaft 29 being driven in any direction and feeding the strip or band 4 forward or backward as the case may be.

Connected with the pawls 49, 50 is a mechanism for controlling the electric circuit of the reversible motor. This mechanism consists of two downwardly projecting swinging bars 52, 53 that are rigidly connected with the pawls 49, 50 in such a manner that, 100 by the up and down movement of the latter, the former will be swung forward and backward. The lower ends of these bars are provided with insulated carbon contact pieces 54, 55. Opposite to the latter carbon contact pieces 56, 57 are secured on longitudinally adjustable spring actuated rods 58, 59. The contact pieces 54, 55, 56 and 57 are electrically connected with the electric source on one hand, and on the other with the reversible electro-motor, there being a hand switch 60 of any suitable construction (Fig. 10) included in the circuit. When, by the attraction of the armature 45, the pawls 49, 50 are lifted, both controllers will be swung forward to bring their carbon pieces 54, 55 in contact with the pieces 56, 57; but owing to a previous switching of the electric circuit of the reversible motor, as, for instance by the hand switch 60 (Fig. 10), the current will be allowed to flow through only one of said controllers, the other remaining inoperative.

Fig. 10 diagrammatically illustrates the electric circuits with relation to the actuati-

ing switch 44 and reversing switch 60, motor 41, contacts 52 and 53, actuating magnet 42 and the source 43. The circuit for the actuating magnet 42 may be traced as follows: source 43, wire 101, actuating circuit closer 44, wire 102, magnet 42, wire 103, back to source 43. The energization of this circuit serves to energize magnet 42 and cause contacts 52 and 53 to close respectively against contacts 56 and 57.

The reversing switch 60 comprises a suitable insulating base 104 carrying terminals 105 and 106 which are connected respectively by leads 107 and 108 with the respective terminals of the source 43. Three contact fingers 109, 110 and 111 are fixed to a central rotatable carrier 112 so as to rotate therewith or as a unitary mechanical structure. Two sets of stationary contacts are fixed to the base 104, namely, one set comprising contacts 113, 114 and 115, to be employed for the rotation of motor 41 in a clockwise direction; and a second set comprising contacts 116, 117 and 118 to be employed for effecting counterclockwise rotation of the motor 41. The insulated wire 119 cross connects stationary contacts 113 and 117. The contact arms 110 and 111 are electrically connected by the wire 120. As shown in Fig. 10, the movable contact fingers 109, 110 and 111 are in a position out of contact with all of the stationary contacts. When the switch is in this position, the circuits presently to be described for effecting the rotation of the motor 41 in either of its two directions are open and consequently no operation of the motor can be effected. For a clockwise rotation of the motor the switch 60 is operated so that contact arm 109 is closed on contact 113; the contact arm 110 is closed on contact 114; and contact arm 111 is closed on contact 115. When the switch is in this position, the circuits for motor 41 may be traced as follows: field circuit, source 43, lead 108, wire 121, wire 122, field of motor 41, wire 123, lead 124, wire 120, contact arm 111, contact 115, wire 125, contact 56, contact 52, wire 126, lead 107 back to source 43. The armature circuit for motor 41 may be traced as follows for clockwise rotation: source 43, wire 108, wire 121, lead 127, contact arm 109, contact 113, wire 128, armature of motor 41, wire 129, contact 114, contact arm 110, wire 120, contact arm 111, contact 115, wire 125, contact 56, contact 52, wire 126, wire 107, back to source 43. For counterclockwise rotation of motor 41, contact arms 109, 110 and 111 contact respectively with stationary contacts 116, 117 and 118. For this position of the switch, the circuit for the field of motor 41 may be traced as follows: source 43, lead 108, wire 121, wire 122, field of motor 41, wire 123, lead 124, wire 120, contact arm 111, contact 118, wire 130, contact 57, contact 53, wire 131, wire 126, lead 107, back to source 43. From the tracing of these circuits it will be seen that the direction of current flow through the field of motor 41 is the same for both positions of the switch 60; whereas the direction of current flow for the armature 41 is reversed by a change in the position of the switch 60; also that the contacts 52 and 56 form a circuit breaker for the circuits for clockwise rotation for motor 41 and the contacts 53 and 57 form a circuit breaker for the circuits for the counterclockwise rotation of motor 41. Thus by the manipulation of the reversing switch 60 the direction of movement of the motor 41 may be altered, whereby upon the actuation of the magnet 42 the motor will be caused to operate in one direction or the other to transmit its movement through the above named friction coupling and set of gears to shaft 29 of the cams 30, 31. By this movement one of the pawls 49, 50 will be caused to slide on the circular portion of its cam and thus hold the corresponding controller closed until, at the end of one revolution of the disk, it meets the eccentric or cam portion of the latter, which causes the pawl to swing down and thereby open the said controller. In consequence thereof, the circuit of the electro-motor is broken and the strip 4 stops, displaying the name of the approaching street or station, or any other matter through the frames at both sides of the casing.

The adjustable mounting of the contact pieces 56 and 57 in the frame 3 provides a convenient means for determining the precise point or moment for cutting off the supply of current to the motor 41. When the bars 52 and 53 are swung forward by the armature 45, the contact pieces 54 and 55 cause the contacts 56 and 57 to retreat against the compression of their respective springs. For the sake of illustration we will suppose the switch 60 to be so set as to send current through the contacts 55 and 57, so that current thus passing will operate the motor to rotate the cams 30 and 31 in a counterclockwise direction, Fig. 7. When the bar 53 was swung and the pawl 50 raised, the concentric portion of the cam 31 passed immediately beneath the head of the pawl and positively prevented a return swing of the bar 53 during something more than a half revolution of the cam. When the cam has reached this position its shape permits of a gradual lowering of the pawl 130

50 and a corresponding gradual return swing of the bar 53 toward its normal position, during the remainder of rotation of the cam. As the contact 55 thus gradually recedes it 5 is followed closely by the contact 57 under diminishing pressure of its spring, and current continues to pass through said contacts to the motor until the preadjusted point is reached at which the contact 57 is stopped. 10 Further movement of contact 55 immediately breaks the flow of current and the motor continues to move by momentum only. The point at which the contact 57 is stopped relative to the cam 31 is preferably adjusted 15 so that the momentum of the motor will rotate said cam through a remaining portion of its revolution with diminishing speed which, while being sufficient to complete the revolution, will yet not cause a 20 damaging shock when the shoulder of the cam engages the head of the pawl. Thus it will be seen that the movement, or rotation, of the cams 30 and 31 serves as the immediate means for determining the movement of 25 the contacts 54-55 during the operation of breaking the electric circuit, and by this means the current through the motor may be discontinued at a point determined by the movement or position of the exhibiting 30 device. The other pawl which was also lifted by the attracted armature is, as soon as the electromagnet is deenergized, allowed to swing down into the corresponding disk and to slide at first on the eccentric or 35 cam portion and then, gradually rising, upon the periphery of the circular portion of the disk. The closure of the corresponding controller effected thereby will, as already indicated, not interfere with the working 40 of the apparatus since the same has no current.

When employing the apparatus in connection with cars to indicate the successive stations or street crossings, at a certain distance from each station or street crossing 45 there may be a projection or the like to automatically operate a switch 44 (Fig. 11) suspended from the passing car.

The switch may be constructed in any 50 suitable manner. In the drawing I have illustrated the same in Fig. 10 by the switch 44 operated in an obvious manner momentarily to close the circuit for actuating magnet 42, which suffices to lift the pawls 55 30, 31 and unlock the cams. Simultaneously therewith the controllers are swung to bring their carbon pieces into contact 60 for starting the motor in the above described manner. The cams are so admeasured that one revolution thereof corresponds with the distance between two successive indications on the strip. Consequently 65 each time the cam is operated to complete a full revolution, a new indication will be displayed through the panes of the casing.

What I claim and desire to secure by Letters Patent is:—

1. In an exhibiting apparatus in combination, an electric motor; an exhibiting device; mechanical connections between said motor and said device for shifting said device; an automatic circuit breaker for said motor comprising a contact automatically and gradually movable to circuit breaking position and controlled by the shifting of said exhibiting device and a coöperating contact yieldingly spring pressed toward and into the path of movement of said first contact; and adjustable means for limiting the travel of said coöperating contact toward said first contact, whereby the engagement between the contacts may be broken before the complete shifting of said exhibiting device. 70 75

2. In a device of the character described, 80 the combination with an indicating strip, of winding rollers, a feed roller, means for imparting movement to said feed roller in opposite directions, loose gears at the ends of said feed roller, ratchet wheels having 85 reversed teeth and being connected with said feed roller, pawls secured to the loose gears and coöperative with said ratchet wheels to automatically couple either of said gears with the feed roller according to 90 the direction of rotation of the latter, a friction coupling for each winding roller, said friction coupling permitting the latter to automatically adjust itself in speed according to the variation of its diameter, and 95 gears transmitting movement from the feed roller to the said friction couplings, said gears being so apportioned that the speed of the winding rollers is greater than that of the feed roller, substantially as set forth. 100 105

3. In a device of the character described, the combination with feed and winding rollers, and an indicating strip, of a reversible electro-motor for driving said feed roller in opposite directions, an automatically operated electro-magnet, a pair of cam disks arranged with their cam portions in reversed direction to one another, a pair of swinging pawls for said cam disks actuated simultaneously by said electro-magnet and independently from one another by the said cam disks, said pawls and cams being adapted to control the feeding of the indicating strip in the respective directions of rotation of the electro-motor, substantially 110 115 as set forth. 120

4. In a device of the character described, the combination with feed and winding rollers and an indicating strip, of a reversible electro-motor for driving said feed roller in opposite directions, an automatically operated electro-magnet, a pair of cam disks arranged with their cam portions in reversed direction to one another, a pair of swinging pawls for said cams, actuated 125 130

- simultaneously by the said electro-magnet, and independently from one another by said cams, electric controllers connected with and actuated by said pawls, of which controllers, one at a time, is adapted to control the electric circuit through the motor to start and stop the latter substantially as set forth.
5. In a device of the character described, the combination with feed and winding 10 rollers and an indicating strip, of a reversible electro-motor for driving said feed roller in opposite directions, an automatically operated electro-magnet, a pair of cams rigidly connected with the feed roller 15 and having their cam portions reversed to one another, a pair of swinging pawls for said cams actuated simultaneously by the said electro-magnet and independently from one another by the said cams, electric controllers comprising spring actuated bars connected with and actuated by said pawls, electric contact pieces carried by said bars, adjustable contact pieces co-operating with said first named contact pieces, of which 20 controllers, one at a time, is adapted to control the electric circuit through the mo- 25
- tor to start and stop the latter, substantially as set forth.
6. In a device of the character described, the combination of a reversible electro-motor, an automatically operated electro-magnet, a pair of cams having their cam portions reversed to one another, a pair of independently swinging pawls simultaneously actuated by the electro-magnet and independently from one another by the said cams, electric controllers connected with and actuated by said pawls, of which controllers, one at a time, is adapted to control the electric circuit through the motor to start and stop the latter at certain points, and a switch for changing the armature circuit of the electro-motor and directing the current through either of said controllers, substantially as set forth.

Signed at New York this 27 day of August 1907.

SAMUEL B. MOSCOVITZ.
